MECHANICALLY OPERATED RAZOR

Ingvar Lonne, Burbank, Calif.

Application October 27, 1944, Serial No. 560,625

4 Claims. (Cl. 30—43)

1

My invention relates to a razor, particularly to the type known as mechanically operating or electric razors.

One of the principal objects of this invention is to provide novel shearing members in a razor of this class for quickly cutting or shaving a beard, whether the hairs of the beard extend directly outwardly or lie at various angles.

An important object of this invention is to provide a razor of this class having shear members provided with such arrangement of shearing edges or such slot means in association with its shearing means that the hairs of the beard to be cut or whiskers to be shaved may easily enter the various slots of the slot means, even though the razor is quickly drawn over the beard or whiskers.

Another important object of this invention is to provide an outer shear member, for a razor of this class, having substantially interwoven slot means across the face thereof, but in which individual slots are not of great length or do not extend the full distance across the face of the shear member, thereby permitting the outer face of the member, which is adapted to engage the skin of the shaver, to be ground or made extremely thin, so that the shearing edges of the razor may come as close as possible to the skin.

A further object of this invention is to provide, in a razor of this class, novelly constructed and arranged outer and inner shear members in which the inner member is reciprocally mounted within the outer member and held between lateral bearing portions so that it may be freely and resiliently forced into engagement with a transversely arcuate shearing surface at the inner side of the outer shear member.

A still further important object of this invention is to provide novel means for operating the inner shear member with respect to the outer member.

Still another object of this invention is to provide a novel resilient connection between the movable shear member and the means for operating the same, whereby substantially all wear is automatically taken up, thereby increasing the efficiency of the shearing means, and also reducing noise to a minimum.

With these and other objects in view, as will appear hereinafter, I have devised a razor having certain novel features of construction, combination, and arrangement of parts and portions, as will be hereinafter described in detail and particularly set forth in the appended claims, reference being had to the accompanying drawings, and to the characters of reference thereon, which form a part of this application, in which:

Fig. 1 is a fragmentary side view of the shearing head portion of a mechanical or electric ra-

zor, embodying my invention, the section being taken through 1—1 of Fig. 2;

Fig. 2A is an enlarged perspective view of the resilient means connecting the operating member to the movable shearing member;

Fig. 2 is a transverse sectional view thereof, taken through 2—2 of Fig. 1;

Fig. 3 is an enlarged end view of the outer shear member of my razor, showing the shearing means in one form;

Fig. 4 is a transverse sectional view through the inner and outer shear members, taken through 4—4 of Fig. 1;

Fig. 5 is an end view, similar to that shown in Fig. 3, of the outer shear member, in a slightly modified form of construction;

Fig. 6 is a side view thereof; and,

Fig. 7 is a transverse sectional view thereof, taken through 7—7 of Fig. 6.

The member 1, shown in Figs. 1 and 2, may be shaped similarly to the motor casing of electric or other razors now in use. This invention relates particularly to the shearing head A, which is held at the outer end of the motor casing.

The shearing head, as shown, consists of an outer shear member 2 having a base 3 at its inner end, an inner shear member 4 reciprocally mounted within a channel 2a of the outer shear member, and a base 5 at the inner end of the inner shear member 4.

The outer and inner shear members are held in U form by the bases 3 and 5, respectively, at their inner ends, so as to provide necessary rigidity at such inner portions.

The outer shear member is provided with a plurality of spaced narrow slots 2b which extend inwardly from the opposite sides and beyond the longitudinal median line of the outer shear member. Thus, the inner portions of the slots 2b overlap each other, as shown in Fig. 3. Such construction of the outer shear member permits the slots to be extremely close together, but does not materially weaken the structure, so that the outer wall or face of the outer shear member 2 may be ground or otherwise fabricated to extreme thinness, in order to bring the shearing edge of the outer shear member as close to the skin of the shaver as possible.

The inner or shearing face, designated 2c, of the outer wall 2d of the outer shear member is arcuate in a transverse direction, and is engaged by a like transversely arcuate face 4a at the outer side of the inner shear member 4. The opposite side walls 4b of the inner shear member 4 are substantially parallel and engage bearing portions of the outer shear member 2. These bearing portions, designated 2e and 2f, are formed by inwardly extending beads in the side walls 2g of the outer shear member.

The beads 2e form grooves at the outer sides of

the side walls and near the outer end of the outer shear member, and the transverse slots 2^b extend through the ridge portions formed between the outer face or wall and such inwardly directed grooves.

In order to effect the shearing action between the shearing members, the inner shear member is provided with transverse slots 4^c which are preferably narrow and spaced apart substantially the distance of the spacing of the slots 2^b.

The inner shear member 4 is reciprocated longitudinally within the channel 2^a by means of an oscillating lever 6 which is operated by any suitable motor (not shown). Over the outer end of the oscillating lever is mounted a spring 7 which pivotally connects the outer end of the oscillating lever with a transverse recess portion 5^a at the underside of the base 5. This spring forces the outer face of the inner shear member 4 against the inner side or shearing surface 2^c of the outer shear member.

The construction of the modified form of the outer shear member, as shown in Figs. 5 and 6, differs from the construction of the member 2 in that the narrow slots 12^b extend inwardly from only a short distance from the opposite edges of the outer shear member 12. The space intermediate the inner ends of the slots 12^b is provided with further slots in the form of crescents 12^c. These crescents are arranged in pairs but are spaced apart at their ends, forming substantially circular slots which are separated at their median portions or on diametric lines. These diametric lines are arranged transversely of the longitudinal extent of the outer face of the outer shear member.

By reason of such arrangement of slots, substantially the whole outer face of the outer shear member is provided with slots into which hairs or whiskers may extend, particularly to receive hairs which may lie at angles other than those extending directly outwardly from the skin.

In this modified form, as in the first described structure, the slots which extend inwardly from the edges are short of the opposite edges, but each structure provides a network of slots or slot means which are so arranged that the outer wall of the outer shear member may be ground extremely thin.

The oscillating member 6 is pivoted at 6^a and is provided with a reduced end 6^b which extends towards the inner or movable shear member 4 for reciprocating the same. Over the reduced end 6^b is positioned the leaf spring 7. It consists of an inner leg 7^a which is threaded over the reduced portion 6^b and is seated against a shoulder 6^d. The outer end of the spring has a turned-back or U-shaped portion 7^b with an enlarged inner end which is partially cylindrical in cross-section and forms a roller which extends into the transverse recess 5^a. The reduced end 6^b on the lever extends into the U-shaped portion. The U-shaped portion is connected with the leg 7^a by means of a loop 7^c.

By reason of such construction, the enlarged or roller part at the end of the U-shaped portion resiliently seats the end of the oscillating arm in the recess 5^a, and this enlarged part of the U-shaped portion 7^b is resiliently forced into the recess 5^a by the loop 7^c.

Though I have shown and described a particular construction, combination and arrangement of parts and portions, and a certain modification

thereof, I do not wish to be limited to the same, but desire to include in the scope of my invention the construction, combination, and arrangements, substantially as set forth in the appended claims.

5 I claim:

1. In a razor of the class described, an outer shear member having a longitudinal channel providing an outer shearing wall and opposite side walls, the side walls having inwardly extending beads spaced backwardly from the outer shearing wall, the inner portions of the beads forming bearing portions, an inner shear member reciprocally mounted within the channel and having an outer shearing wall engaging the shearing wall of the first member, and also provided with parallel side walls slidably engaging the bearing portions of said beads, and means for resiliently forcing the shearing surface of the inner member against that of the outer member.

20 2. In a razor of the class described, an outer shear member having a longitudinal channel providing an outer shearing wall and opposite side walls, each of the opposite side walls having inwardly extending parallel ridges, the inner portions of the ridges forming bearing portions, an inner shear member reciprocally mounted within the channel and having an outer shearing wall engaging the shearing wall of the first member, and also provided with parallel side walls slidably engaging each of the bearing portions, and means for resiliently forcing the shearing surface of the inner member against that of the outer member.

25 3. In a razor of the class described, an outer shear member having a longitudinal channel providing an outer shearing wall and opposite side walls, an inner shear member reciprocally mounted within the channel and also having an outer shearing wall engaging the shearing wall of the first member, the first member having inwardly extending ridges near the inner end of the inner shear member, the inner portions of the ridges forming bearing portions for the inner ends of the side walls of the inner shear member, and means for resiliently forcing the shearing surface of the inner member against that of the outer member.

40 4. In a razor of the class described, a stationary shear member on the support, a movable shear member, an oscillating member on the support, said oscillating member having a reduced portion at the free end, and a spring member having a leg threaded over and positioned backwardly from the end of the reduced portion of the oscillating member, and also having a U-shaped leg positioned at right angles to the first leg and over the end of the reduced portion, the U-shaped leg being connected by a loop with the first leg, the U-shaped leg extending into a recess of the movable shear member.
